ABRADING APPARATUS

Walter L. Keefer, Hagerstown, Md., assignor to
 Pangborn Corporation, Hagerstown, Md., a corporation of Maryland

Application July 23, 1941, Serial No. 403,720

12 Claims. (Cl. 51—9)

This invention relates to abrading apparatus and more particularly to a centrifugal wheel for projecting abrasive such as steel grit and shot at an abrading velocity upon workpieces to be cleaned.

Machines of the type herein described may be said to consist of three main parts, namely, a rotor including one or more abrasive propelling blades thereon, an abrasive supply means, and a transfer mechanism which functions to transfer the abrasive from the supply means to the blade, or blades, on the rotor in such manner that the abrasive is discharged onto the inner ends of the blades at a predetermined point or zone, the abrasive subsequently being discharged from the ends of the blades in a predetermined zone.

It has been proposed heretofore to provide a transfer mechanism having an abrasive opening for each blade, the several passages being maintained closed by mechanically operated valves except at a predetermined point in the rotation of the transfer mechanism where the mechanical means opens the valves and releases the abrasive onto the adjacent blade. Such prior devices have been characterized by the disadvantage of pivoted valves and mechanical operating means therefor which are susceptible to rapid deterioration by the abrasive particles. Such prior devices have also required additional means to impart the necessary velocity to the abrasive which is desirable to secure more concentrated blasts and better directional control in any desired direction of discharge.

In providing an improved centrifugal wheel of the valved transfer type, it is an object of this invention to provide a novel valved transfer mechanism of relatively simple construction wherein pivoted valves and operating means therefor are eliminated, there being no mechanical means susceptible of damage by the abrasive.

Still a further object of this invention is the provision of a novel valved transfer mechanism wherein advantage is taken of the already present propelling blades of the rotor to both rotate the transfer mechanism and to operate the valve means thereof.

A further object of this invention is the provision of a novel centrifugal wheel employing a valved transfer means wherein the abrasive received therein may be discharged at any predetermined point and in highly concentrated charges without the necessity of so-called additional impelling or agitating means.

Still a further object of this invention is the provision of a novel centrifugal wheel of the

valved transfer type wherein the parts are of relatively simple construction, of longer life, and are easily accessible for replacement and repair.

Further objects and advantages of this invention will appear from the following description and claims, taken in connection with the attached drawings, wherein:

Fig. 1 is a central section through a centrifugal wheel representing a preferred embodiment of the invention taken on the line 1—1 of Fig. 2.

Fig. 2 is a section taken on the line 2—2 of Figure 1 through the transfer mechanism, the remaining portion of the wheel including the rotor and the blades thereon being shown in elevation.

Fig. 3 is a section taken on the line 3—3 of Fig. 2 illustrating an auxiliary means for communicating rotation of the rotor to the transfer mechanism.

Fig. 4 is a front elevation of the abrasive supply means and the supporting means for the transfer mechanism and the means whereby the mechanism can be adjusted to change the discharge of the abrasive from the periphery of the wheel from one point or zone to another point or zone.

Fig. 5 is a front elevation of the combined impeller and transfer mechanism of Figures 1 and 2.

Fig. 6 is a perspective of one of the valve members employed in the impeller of Fig. 5.

Referring to Figure 1, the centrifugal wheel there shown is mounted in conventional manner on a shaft 11 mounted in suitable bearings and arranged to be rotated by suitable driving means such as an electric motor (not shown). The wheel is enclosed in a housing in conventional manner, one wall of the housing being shown at 12 with a wear plate 13 secured thereto to protect the housing against wear from the flying abrasive. It is to be understood that the housing has one side open, usually at the bottom or side, through which the abrasive, such as steel shot and grit, is discharged onto the workpiece to be blasted.

A rotor proper 14 is supported on the end of shaft 11 for rotation therewith by a flange 15, the rotor proper including a disc 16, a plurality of sector plates 17, and one or more abrasive propelling blades 18. Sector plates 17 are detachably secured to the face of disc 16 by suitable fastening means, the edges of the sector plates being spaced apart and their adjacent edges beveled so that they cooperate with the face of disk 16 to define radial extending dovetail-shaped grooves. Blades 18 are provided with correspond-

ingly dovetail-shaped bases which fit within the aforementioned grooves. For a further description of the sector plates and the manner of holding the blades in position upon the face of the rotor disk, which does not form a part of the present invention, attention is called to United States Patent No. 2,246,522, issued June 24, 1941.

The disk 16 may extend completely across flange 15, but it is preferred to provide an opening in the center of the disk to receive a dished plate or retainer 19 secured therein by a bolt 21 entering flange 15. Retainer 19 is provided with a circumferential, axially extending flange 22 that functions to help retain the valve members in the impeller in a manner to be described.

Each blade 18 includes a propelling surface 23 onto which the abrasive is discharged and side flanges 24 and 25 which prevent the abrasive from escaping sidewise from the propelling surface. Flanges 24 and 25 terminate at a point spaced from the inner end of the blade to leave a flangeless extending portion 26 which functions in the valving of the abrasive from the impeller in a manner to be later described.

The abrasive supply means or feed means includes a feed spout 27 into which abrasive is fed, as by gravity, from a hopper positioned above the wheel. For support, feed spout 27 is formed with a flange 28 at its upper end having holes 29 therein which fit over pins 31 projecting from an angle bracket 32 secured to wall 12 of the housing.

An opening 33 is provided in wall 12 and wear plate 13 into which is fitted a holder 34 having a cylindrical section 35 and a flange 36 which fits against the outside of wall 12. Studs 37 are mounted in wall 12 to receive clamps 38 engaging flange 36. By this arrangement, holder 34 can be rotated to any desired position and clamped therein, suitable nuts being threaded on studs 37 to secure the clamps.

To center the holder 34 and insure its so remaining, three studs 39 are mounted in wall 12 with small cams 41 and nuts 42 thereon. By rotating cams 41 which contact the outer periphery of flange 36, the holder can readily be centered, the cams thereafter being locked by nuts 42 and preferably welded in position to insure against their becoming loosened.

Adjacent its center, holder 34 is formed with a shouldered opening 43 into which is telescopingly fitted a circular section 44 on the lower end of feed spot 27. A gasket 45 is preferably provided in coonnection with the telescoped parts to prevent the leakage of abrasive around the joint thus formed.

The lower end of spout 27 is provided with a flange 46 adjacent a bolt 47, secured in holder 34, and mounting a clamp 48. When holder 34 is to be rotated to a new position, bolt 47 is loosened and subsequently tightened after holder 34 has been adjusted. To enable clamping when holder 34 is rotated as much as 180°, or even less, holder 34 may be provided with other tapped holes to receive bolt 47. This arrangement insures proper support of the lower end of the feed spout in all positions of holder 34.

The holder 34 is formed with a projecting central section or boss 49 which is recessed at 51 to form a passage 52 connecting with the discharge end of feed spout 27 and serving as a continuation thereof. Passage 52 is preferably shaped in cross-section, as shown in Fig. 2, the wall defining the right side, as viewed in Fig. 2, being somewhat shortened and rounded as at 53 to facilitate

the discharge of abrasive in the direction in which the wheel rotates, or counterclockwise, as viewed in Fig. 2. It will be noted that in the abrasive feed passage defined by the feed spout 27 and the passage 52, there are no abrupt bends to hinder the flow of abrasive, the latter being able to flow into the transfer means in a substantially straight and unobstructed path.

The boss 49 is bored on an axis offset from or eccentric of the axis of rotor 14 to support one end of a shaft 54 which is flanged at 55 to fit within a recess 56 in the end of the bore. To insure shaft 54 remaining in a fixed position in its bore, it is preferably welded therein as shown at 57, the left end of the shaft (Fig. 1) being shaped to conform to the contour of passage 52 and maintain a free unobstructed passage for the abrasive.

The shaft 54 is provided with a bearing 57a upon which is supported a hub 58 of a cage-like member or impeller 59, hub 58 being of truncated conical shape to fit within the concave end of boss 49. Hub 58 is preferably reinforced by ribs 60 and is formed with a flange 61 which supports a series of circumferentially arranged elements 62, each of said elements defining an abrasive passage 63 with the next adjacent element, said passages leading to the exterior of the impeller.

While element 59 is referred to as an impeller, it is to be understood that it serves also as means for effecting the discharge of abrasive onto the inner ends of the rotor blades at a predetermined point. By reason of its double function as hereinafter explained, the single element can be employed to discharge abrasive at any selected point around its periphery at a considerable velocity without the need of any additional agitating or abrasive impelling means.

On its leading face, each element 62 is formed with a substantially radial short face 64 merging into a forwardly curved surface 65 which terminates in an abruptly reversed surface 66.

The trailing face of each element 62 is formed by an outwardly and rearwardly inclined surface 67, preferably formed at an angle of about 107° to a radius, leading into a curved surface 68 which continues to a surface 69 at which the abrasive is discharged. It will be noted that the outer end of surface 68 is slightly dished at 70 to function as a valve seat.

Each element 62 is formed with a partially cylindrical recess 71, the outer end of which is partly closed by an inwardly projecting section 72, curved on its inner surface to function as a valve seat. Recess 71 is open at both ends of the impeller to permit the ready insertion and removal of a valve member 73 of cylindrical shape (Fig. 6) and formed of relatively soft material, such as rubber.

Adjacent the right end of the impeller as viewed in Fig. 1, and around the periphery, a series of webs 74 are provided connecting a portion of the trailing face of the elements 62, and the section 72. Each of webs 74 is recessed at 75 to form a yoke which is arranged to receive a pin 76 mounted in disk 16 (Fig. 3) and extending through sector plate 17. Pins 76 operate as auxiliary means to insure rotation of the impeller at the same speed as the disk in the event that the primary means hereinafter described fails. As the impeller is mounted on an axis which is offset with respect to the axis of the disk, the yoke connection with a pin 76 is essential to permit the eccentric travel of the impeller.

The inner portions of elements 62 are extend-

ed axially from hub 58 toward holder 34 where they are connected by a flange 77 which functions to protect the interior mechanism from the action of the abrasive particles.

The holder 34 is formed with a circumferentially projecting flange 78 which terminates adjacent the left end of each of valve members 73 to prevent the valve members slipping forward in their seats 71, rearward slippage of the valve members being prevented by flange 22 on retainer 19.

In operation, the disk 16 is rotated at an abrading speed by the drive means connected thereto. The impeller or cage-like member 59 is rotated at the same speed by reason of the inner ends 26 of blades 18 engaging the faces 69 of the several passages 63. This action is analogous to the drive of an internal gear by an external gear, and prevents the impeller getting out of synchronism with the disk since one blade tip 26 is always driving through contact with a face 69 while the face of a section 72 prevents the impeller from running ahead of the disk. In event of the breaking of one or more of the blade tips, continued rotation of the impeller with the disk will be assured by the engagement of pins 76 with yokes 75.

Abrasive fed through spout 27 is discharged in the embodiment shown inside the impeller, and at the bottom thereof. A charge of abrasive S from the end of the feed spout is picked up by the forward face 64 of each element 62, the charge S continuing along surface 65 by reason of centrifugal force during continued rotation of the impeller and finally discharging therefrom onto surface 68, and there collecting at S', as shown in Fig. 2. It will be noted that in all these positions of the abrasive that the element 62 by which the abrasive is being collected has its valve member 73 in closed position by reason of centrifugal force, the valve member sealing the opening to the exterior of the impeller by reason of its contact with valve seats.

Upon reaching the point designated at A in Fig. 2, the inner end 26 of the adjacent blade 18 comes into contact with valve 73. With continued rotation of the blade and impeller, the impeller moves outwardly, the blade moving correspondingly inwardly relative to the abrasive passage 63 to a point shown at B wherein the valve member 73 has been pushed inwardly away from its seating surfaces, whereupon the abrasive collected upon the surface 68 is discharged by centrifugal force onto the inner end of the blade with considerable velocity.

Upon continued rotation of the wheel, the charge of abrasive flows outwardly over the surface of the blade, and is discharged at the periphery of the wheel in well known manner at a point beginning approximately 90° from point B.

In the continued operation of the wheel, the eccentric action of the impeller causes the inner ends of the blades to recede relatively from valves 73 and permits the valves to seat under the action of centrifugal force and close passages 63. The arc over which the valves are closed is approximately 270°, the open range being about 90°. At about the 12 o'clock position or about the point A in the embodiment shown, the blade ends begin to open the valves, permitting the abrasive charges to slide out of the passages onto the blades, the abrasive being accelerated to abrading velocity as it moves outward over the vane surface. At approximately the 10:30

o'clock position or about point B, the valve is fully opened and then begins to close.

In so operating, it is believed that the impeller functions both as a charge forming device and as means to impart considerable velocity to the abrasive as it is discharged from the passages 63. The formation of the individual charges of abrasive is as already described. By reason of the shapes of the walls of passages 63, the charges are readily formed and subsequently maintained in a position where they can be quickly discharged. The opening of the valves is comparable to the releasing of one end of a rapidly rotating sling. While the shot in the sling has no movement relative to the sling while the latter is being slung, it flies from the sling at considerable velocity when the sling is released. Likewise, while the abrasive charges, once collected, do not move relative to the impeller while the valves are closed, they are discharged therefrom at a considerable velocity when the valves are opened. This velocity results in an improved abrading stream both as to abrading properties and directional control.

While the embodiment described is a downblast wheel, it is to be understood that by rotating holder 34 and changing the point of eccentricity of the impeller axis, the direction of the stream of abrasive can be adjusted to the left or right.

Obviously the stream can be caused to discharge at any point in 360° by changing the point of eccentricity of the impeller axis. It is preferred that the discharge end of the feed spout at 52 remain in substantially the same position regardless of the position of the impeller axis.

The action of the abrasive in passing over the valve seats is not severe, since at this radius the abrasive velocity is relatively low and the surfaces 68 are retreating as the abrasive slides thereacross, thereby reducing the pressure of the abrasive. Even with considerable wear on the valve seats, the valves will continue to function because of their elasticity and ability to conform to irregular surfaces. Actual wear on the valves is minimized because there is no movement of abrasive across the valve when it is closed, and when it is open the valve is thrust inwardly into its semi-cylindrical chamber wherein it is protected from the abrasive.

It is to be understood that the invention may be embodied in specific forms other than that illustrated without departing from the principle or essential characteristics thereof. The embodiments shown are therefore to be considered as illustrative and not restrictive, the scope of the invention being defined by the appended claims rather than the foregoing description and drawings. All modifications and changes which come within the meaning and range of equivalency of the claims are therefore intended to be included therein.

I claim:

1. In an abrading apparatus, a rotor having a plurality of abrasive propelling blades, the inner ends of said blades being spaced apart to define a central opening, means to feed abrasive into said central opening, and means to transfer said abrasive to the inner ends of said blades comprising a cage-like member formed with a passage in its periphery adjacent the inner ends of each of said blades, and valve means to normally close each of said passages, said member being mounted to rotate about an axis sufficiently eccentric of said rotor axis to bring the orbit of the inner end 70 of the blades within the orbit of said valve means

to thereby cause said valve means to be opened by the inner ends of said blades at a predetermined point.

2. In an abrading apparatus, a rotor having a plurality of abrasive propelling blades, the inner ends of said blades being spaced apart to define a central opening, and means to feed abrasive onto the inner ends of said propelling blades comprising a cage-like member arranged to rotate at the same speed as said rotor about an axis offset from and parallel to the rotor axis, means to feed abrasive into said member in a substantially continuous stream, a series of blades in said member arranged to divide said abrasive stream into a series of individual charges, one for each of said blades, and to conduct said charges to the outer periphery of said member, and means to normally prevent the discharge of said abrasive charges from said member, said latter means being arranged to be rendered inoperative by said abrasive propelling blades at a predetermined point in the rotation of said rotor.

3. In an abrading apparatus, a rotor having a plurality of abrasive propelling blades, the inner ends of said blades being spaced apart to define a central opening, means to feed abrasive into said central opening, and means to transfer said abrasive from said feed means to the inner ends of said blades comprising a cage-like member mounted to rotate at the same speed as said rotor and on an axis displaced with respect to the rotor axis receiving abrasive from said feed means, a plurality of openings in the wall of said member, means to normally close said openings, and means on the inner ends of said blades to render said last-mentioned means inoperative at a predetermined point in the rotation of said rotor.

4. In an abrading apparatus, a rotor having a plurality of abrasive propelling blades, the inner ends of said blades being spaced apart to define a central opening, means to feed abrasive into said central opening, and means to transfer abrasive from said feed means to the inner ends of said blades comprising a cage member mounted to rotate at the same speed as said rotor, said member having a valve cage in its periphery adjacent the inner end of each of said blades, said member having an opening adjacent each of said valve cages leading from the interior of said member to its exterior whereby abrasive may pass from the interior of said member onto the inner ends of said blades, a valve in each of said valve cages arranged to close said openings under the action of centrifugal force, and means supporting said member on an axis sufficiently eccentric of the axis of said rotor whereby the inner end of each blade engages and opens the corresponding valve at a predetermined point in the rotation of said rotor to effect delivery of abrasive onto the inner end of said blade at said predetermined point.

5. In an abrading apparatus, a rotor having a plurality of abrasive propelling blades, the inner ends of said blades being spaced apart to define a central opening, abrasive feed means extending into said central opening, and means to transfer abrasive from said feed means to the inner ends of said blades comprising a cage-like member arranged to receive abrasive in its interior from said feed means, means on said feed means to support said member for rotation about an axis eccentric of the axis of said rotor, said member having an opening in its periphery adjacent the inner end of each blade, a valve in each of said

openings arranged to close said openings under the action of centrifugal force when said member is rotated, and the inner end of each of said blades being adapted to engage and open the corresponding valve at a predetermined point in the rotation of said rotor to permit the delivery of abrasive onto the inner end of said blade, and to engage said member to cause the latter to rotate at the same speed as said rotor.

6. In an abrading apparatus, a rotor having a plurality of abrasive propelling blades, the inner ends of said blades being spaced apart to define a central opening, abrasive feed means extending into said central opening, and means to transfer abrasive from said feed means to the inner ends of said blades comprising a cage-like member mounted to rotate at the same speed as said rotor on an axis displaced from the rotor axis and having a series of passages extending from the interior to the exterior, there being one passage for each of said blades, said feed means being positioned to discharge abrasive into said passages at a predetermined point in the rotation of said member, centrifugally operated valve means to normally close said passages, and means on the inner ends of said blades to open said valve means at a second predetermined point in the rotation of said member to permit the feed of abrasive onto the inner ends of said blades.

7. In an abrading apparatus, a rotor having a plurality of abrasive propelling blades, the inner ends of said blades being spaced apart to define a central opening, abrasive feed means extending into said central opening, and means to transfer abrasive from said feed means to the inner ends of said blades comprising a cage-like member mounted to rotate at the same speed as said rotor and having a series of passages extending from the interior to the exterior, there being one passage for each of said blades, an axially-extending open-ended semi-cylindrical valve cage associated with each of said passages, a cylinder of relatively soft material in each of said cages, said cylinder being arranged to maintain said passage closed under the action of centrifugal force, and means for moving each cylinder to a position for opening an associated passage at a predetermined point in the rotation of said rotor.

8. In an abrading apparatus, a rotor having a plurality of abrasive propelling blades, the inner ends of said blades being spaced apart to define a central opening, abrasive feed means extending into said central opening, and means to transfer abrasive from said feed means to the inner ends of said blades comprising a cage-like member mounted to rotate at the same speed as said rotor on an axis displaced from the rotor axis, said member having a passage in its peripheral wall corresponding to each blade, said passage being arranged to discharge at a point in advance of the propelling surface of said blade, a valve in said passage, and means on the inner end of said blade to engage and open said valve at a predetermined point in the rotation of said rotor, said last mentioned means being rearwardly of the point of discharge of said abrasive.

9. In an abrading apparatus, a rotor having a plurality of abrasive propelling blades, the inner ends of said blades being spaced apart to define a central opening, abrasive feed means extending into said central opening, and means to transfer abrasive from said feed means to the inner ends of said blades comprising a cage-like member arranged to receive abrasive in its interior from said feed means, means on said feed means

to support said member for rotation about an axis eccentric of the axis of said rotor, a driving connection between said rotor and said member for rotating the member at the same speed as the rotor, said member having a series of passages extending from its interior to its exterior, an open-ended axially-extending semi-cylindrical valve cage associated with each of said passages, a cylindrical valve in each of said valve cages, said valve being arranged to close said passage under the action of centrifugal force, means on said member-supporting means and said rotor to prevent axial displacement of said valves, and means for moving each cylindrical valve to a position for opening an associated passage at a predetermined point in the rotation of said rotor.

10. A transfer mechanism for use with a centrifugal abrading rotor comprising a cage-like member mountable for rotary movement and having a series of passages extending from the interior to the exterior, an axially extending open-ended semi-cylindrical valve cage associated with each of said passages, a cylinder of relatively soft material in each of said cages, said cylinders being larger than the opening at the outer end of the passages to maintain said passages closed under the action of centrifugal force, and said cylinders being movable inwardly to open said passages.

11. In abrading apparatus, a rotor, a plurality

5 of abrasive propeller blades on said rotor with the inner ends thereof defining a circular space concentric with the axis of said rotor, a cage member rotatably mounted in said space on an axis parallel to but displaced from the axis of the rotor and rotating at the same speed as said rotor, said cage member having a plurality of passages therein, movable means normally closing each passage, the eccentricity between said rotor and 10 said cage member being such that during rotation of the cage member about the axis thereof eccentric movement of the cage member relative to the rotor will urge one of said movable means into engagement with an inner end of one of said 15 propeller blades to open the associated passage at a predetermined point in the rotation of said rotor.

12. In centrifugal abrading apparatus, a rotor including a plurality of propeller blades extending 20 inwardly short of the axis of the rotor, a cage member rotatably mounted between the inner ends of said propeller blades on an axis substantially parallel to but displaced from the axis of the rotor, webs on the cage member each having 25 a peripheral recess therein, and a plurality of pins carried by the rotor arranged to outline a circle concentric with the axis of the rotor and adapted to engage said webs within said recesses to drive the cage at the same speed as said rotor.

WALTER L. KEEFER.
